ALBERT A. DENSMORE, OF BOSTON, MASSACHUSETTS, ASSIGNOR TO ECLIPSE MACHINE COMPANY, OF ELMIRA HEIGHTS, NEW JERSEY, A CORPORATION OF NEW YORK

POWER TRANSMISSION MECHANISM

Application filed June 10, 1922. Serial No. 567,311.

This invention concerns power transmission mechanism and relates more particularly to engine starting devices.

The usual type of electrically driven starter for internal combustion engines comprises a pinion which is driven by the armature shaft and which is automatically moved into and out of mesh with a gear carried by the engine shaft. In some installations the pinion is provided with means intended to prevent its rotation with the armature shaft prior to its engagement with the engine gear, but in practice such means are sometimes found inadequate, due for example to the accumulation of dirt, gummy oil, etc. upon the engaging parts, so that the pinion may be caused while rotating at high velocity to approach and contact with the gear, thus producing a disagreeable noise or may fail to traverse into engagement with the gear until the actuation of the starting motor is repeated.

The ordinary starter moreover is limited with respect to the capacity of the drive for yielding under overload. When, therefore, as may happen through carelessness on the part of the operator or for other reason, the engine back fires in starting, the automatic starting mechanism is thereby subjected to heavy stresses which may be objectionable.

Objects of the present invention are to provide a starter of a type of such character as to assure intermeshing of the pinion with the engine gear prior to rotation of the pinion, and under substantially all conditions of use, and also to provide connections between the starting motor and pinion of a character such as to permit reverse rotation of the pinion relatively to the armature shaft under extraordinary conditions, such for example as back firing of the engine, the connections however being adapted under ordinary circumstances to transmit movement of the armature shaft to the pinion for starting the engine in the proper direction.

For attaining the above objects, a screw clutch is preferably employed, such clutch comprising cooperating threaded parts to one of which the drive pinion is connected, and by relative rotation of which the pinion

is caused to move axially into mesh with the engine gear prior to its rotation with the other of said parts by the armature shaft. For producing such relative rotation of the screw threaded parts, the other of such parts is so connected to the armature shaft as to partake of the rotation thereof under normal working conditions, while being capable of relative movement in the reverse direction when subjected to sufficient turning force. Preferably such connections comprise a cam element and a second element normally engaging the same but having no positive connection thereto, together with a spring for opposing relative movement of rotation of said elements. One of said elements is secured to the armature shaft and the other to the driving part of the screw clutch, the spring being of sufficient strength to insure transmission of the normal driving force from one of said elements to the other while permitting reverse movement of the driven element relatively to the drive element upon application of sufficient force, as for example, in back firing of the engine.

In one form of the device the engaging elements comprise complementary cam surfaces carried by the opposed end faces of a pair of aligned, cylindrical blocks, one of such blocks being secured to the armature shaft and the other being carried by a sleeve constituting the driving member of a screw clutch. The latter block is urged toward the first block by a heavy spring the tension of which may be adjusted, so that relative turning of the complementary cam elements is limited by the compressibility of the spring. In normal running the cam blocks assume a certain angularity depending upon the power transmitted and upon the strength of the spring, but upon back firing of the motor, the driven block reverses, first further compressing the spring, and then as the maximum elevations of the cam surfaces are passed relieving the spring of such tension, such increase and decrease in tension being repeated until the energy of back fire has ceased whereupon the armature shaft automatically picks up the driven element ready for a new attempt at starting. Thus the starter may

operate continuously irrespective of back firing and without danger of breakage or injury of parts. While it is contemplated that some of the advantages of the present device might be secured by the use of a shear pin between certain of the driving connections and which would, upon back firing, be sheared off; thus avoiding breakage of more important and costly elements, such an arrangement necessitates some delay at least, and is regarded as decidedly inferior to the arrangement above referred to. While spring controlled cam elements are very efficacious in attaining the results wished for, it is contemplated that other and equivalent means may well be employed for attaining the desired objects, it being regarded however, as very desirable that the driving means involve entirely independent elements having no positive connection so that while normally operative to turn simultaneously in the same direction, one may turn to any requisite amount in a reverse direction without breaking parts or necessarily stopping or reversing the other.

In order to avoid any possibility of the pinion partaking of the rotation of the armature shaft prior to its engagement with the engine gear it is preferred to employ a device in the nature of a brake which in the inoperative position of the parts bears against the end face of the pinion with sufficient force to prevent rotation of the same. Preferably this brake device consists of a brake disk coaxial with the pinion and forced against the end face of the latter by means of a coil compression spring. In the inoperative position of the parts this spring is under maximum compression, but as the pinion is moved axially toward the engine gear by the screw clutch device the force of the spring gradually diminishes until at the instant the pinion fully meshes with the gear, the braking effect of the disk is substantially eliminated. It is thus evident that at the instant of starting of the armature shaft the pinion is most strongly held against rotation so that any accumulation of dirt or gum between the pinion and its driving element such as would tend to carry the pinion with the driving element as the latter rotates is rendered ineffective by the brake, while as the pinion assumes driving position it is substantially freed from contact with the brake and thus during driving no substantial frictional brake effect remains.

In the accompanying drawings there is illustrated by way of example an arrangement of parts well adapted to secure the desired objects and in such drawings:—

Fig. 1 is a side elevation, partly in vertical longitudinal section, of an engine starting mechanism of a preferred form, showing the parts in initial, inoperative position;

Fig. 2 is a side elevation of the device

shown in Fig. 1, the parts being shown, however, as in position for driving the engine gear;

Fig. 3 is a view similar to Fig. 1, but illustrating a modification;

Fig. 4 is a view similar to Fig. 1, but illustrating a further modification;

Fig. 5 is a fragmentary, longitudinal cross section, to somewhat larger scale than the preceding figures, and illustrating a still further modification;

Fig. 6 is a vertical cross section on the line 6—6 of Fig. 5; and

Fig. 7 is a plan view illustrating a detail of one of the elements of the device shown in Figs. 5 and 6.

Referring to Figs. 1 and 2, an internal combustion engine of any usual type is indicated at 1, such engine having a shaft provided with a fly wheel 2 having a spur gear 3 secured to or integral with its rim. It is to be understood, however, that such gear might, if desired, be mounted independently upon the engine shaft or might even be carried by a separate shaft driven from the engine. An electrically operated starting motor 4 of usual type, is also shown, such motor having an armature shaft 5, and being mounted upon any suitable support. Secured to the shaft 5 is a yoke member or attaching collar 7 comprising a sleeve portion 8 into which the shaft extends and to which it is secured by means of a pin 6. This sleeve portion is provided with an enlarged hub element 9 which is preferably provided with a square socket with which engages the square end 10 of a shaft 11 which aligns with, and is in effect an extension of, the armature shaft 5. The opposite end of this shaft turns in a bearing 12 provided in a bracket 13 secured in any desired manner to the engine frame. A hollow shaft or sleeve 14 is mounted upon the shaft 11, turning freely thereon, such sleeve being provided with a radially projecting pin 16 engaging a circumferential groove upon the inner surface of a cylindrical cam block 17. This cam block is externally screw threaded, as indicated at 18, for engagement with internal screw threads 19 upon the inner surface of the yoke member 7, the cam block being thus adjustable longitudinally with respect to such yoke member. For holding the parts in adjusted position a set screw 20 may be provided. With the parts as thus arranged, it is clear that rotation of the armature shaft 5 will rotate the yoke 7 and the shaft 11 and that rotation of the yoke will turn the cam block 17 which forms in effect a rigid though adjustable part thereof. Rotation of the cam block however, is not directly transmitted to the sleeve 14, as the pin 16 moves freely in the groove 15, this groove, however, providing against relative longitudinal movement of the cam block and sleeve. A second

115

120

125

130

cam block 21 is also mounted upon the sleeve 14, this latter block having a pin 22 which engages a keyway 23 in the sleeve 14. This cam block is thus free to move longitudinally of the sleeve while the sleeve is compelled to rotate with the cam block.

The cam blocks 14 and 21 are provided with complementary cam faces 24, 25 respectively, such faces being inclined with respect to the axis of the shaft 11, it being understood, however, that any desired variation in the respective cam faces may be employed such as may prove to give the best results under special conditions of use. The cam block 21 is provided at its right-hand end, as viewed in Fig. 1, with an annular flange 26 which defines a seat for one end of a coil spring 27 which surrounds the sleeve 14. The sleeve 14 is externally screw threaded at its right-hand extremity (as viewed in Fig. 1) for engagement with screw threads upon the interior surface of a flanged abutment member or stop collar 28, such abutment member being provided with an annular flange 29 defining a seat for the opposite end of the spring 27. The abutment member 28 is adjustable longitudinally of the sleeve 14 by its screw threaded connection therewith, but may be secured in adjusted position by means of a set screw 30 so as to form in effect a rigid part of said member 14.

At its right-hand end the sleeve 14 is provided with an enlarged bore 31, the interior surface of which is screw threaded so that the threaded annular wall forms in effect a nut of collar portion of which collar 28 is, in effect, a circumferential extension. A pinion 32 is mounted to turn freely on the shaft 11, such pinion being provided with an extended hub 33 constituting a sleeve or hollow shaft mounted upon the shaft 5 of the motor and being externally screw threaded for engagement with the screw threads upon the interior surface of the bore 31. The bore 45 and the hub are of such relative lengths as to permit a stop on the screw sleeve or hub 33 to be brought into contact with the end surface 34 of the abutment member 28 the side of the pinion here serving as such stop and, 50 the pinion when in this position meshing with the gear 3 of the engine shaft.

Preferably a brake disk 35 is mounted upon the shaft 11 to slide freely thereon, and is held in frictional contact with the end face of pinion 32 by means of a coil spring 36 interposed between such disk and a second disk 37 which contacts with the bearing 12. The length and tension of the spring 36 are so determined that when the pinion 32 has been brought into engagement with the surface 34 of the abutment, the spring is substantially relieved from all compressive stress and the brake disk 35 bears with little, if any pressure against the face of the pinion.

The operation of the device thus described

is substantially as follows, it being assumed that the parts normally occupy the position indicated in Fig. 1 and that the engine gear 3 is stationary. Upon starting the motor 4 the shaft 5, yoke 7 and cam block 17 are simultaneously rotated. The first effect of this is to place the spring 27 under slight compression due to the axial reaction of the cam faces 24 and 25. Only a slight compression of the spring is at first necessary to cause the cam 75 block 21 to rotate with the armature shaft, thus turning the sleeve 14 relatively to the hub of pinion 32 and drawing such hub axially into the bore 31 until the pinion meshes with gear 3 and comes into contact with the 80 abutment surface 34. During such movement, the action of the brake disc 35 tends to restrain the pinion 32 against rotation with the sleeve so that as the pinion approaches the gear the parts move into mesh smoothly 85 and noiselessly and without any tendency to break the edges of the teeth of the gear or pinion. As no further axial movement of the pinion relatively to the sleeve is now possible 90 the pinion is compelled to take up the movement of rotation of the sleeve, the effect of the brake disc 35 at the end of the axial movement of the pinion becoming substantially nil. Turning of the pinion is, however, opposed by the inertia of the engine parts and 95 thus the cam block 17 may be caused to slip relatively to cam block 21. Such relative rotary movement of these parts results in compressing the spring 27 to a greater degree until finally the resistance to further 100 compression of the spring equals the force necessary to turn the cam block 21 whereupon the latter block turns synchronously with block 17 and the pinion 32 acts to rotate the gear 23 for starting the engine. The parts 105 continue to operate in this manner until the engine has picked up normal speed, whereupon the pinion is driven by engagement with gear 3 at a speed sufficiently greater than that of the sleeve 14 to cause the hub 110 33 to retreat from the bore 31, thereby disengaging the pinion 32 from the gear 3 and at the same time compressing the brake spring 36. The starting motor 4 is automatically 115 stopped as soon as the pinion has been disengaged by the usual means employed for such purposes, and which is not herein disclosed. The spring 27, compressed while the starting load is being carried, tends, when the starting apparatus is relieved of such 120 lead, to move the cam block 21 back to position shown in Fig. 1 and thus to cam the blocks 21 and 17 to their normal relative position. Such restoration is not absolutely necessary, however, as when the starting motor is again actuated, the compressibility of the 125 spring 27 serves in any case to determine the relative positions of the cam faces 24 and 25 at which rotation of the block 21 for driving pinion 3 shall be initiated.

With the arrangement above described, if for any reason, as for example as through carelessness on the part of the operator, the engine should back-fire while the pinion 32 is in mesh with the gear 33, the reverse rotation of the sleeve thereby occasioned may take place without in any manner interfering with the operation of the armature shaft 5. In such case, the first action is to move the cam faces 24 and 25 in such direction as to compress the spring 27 somewhat more than the normal amount and possibly sufficient to permit the high points of the cam faces to pass each other, thereupon the spring immediately snaps the cam block 21 back to starting position, axially of the shaft, from which it is again moved by the relative reverse rotations of the armature shaft and the sleeve. This operation is repeated so long as the momentum imparted to the sleeve 14 by the back-firing action subsists, but after such momentum has been overcome, the armature shaft again operates the parts in normal fashion in a further attempt to start the engine. Thus, the back-firing has no substantial effect on the starting mechanism except momentarily to increase the compression of the spring 27 and the parts thus remain integral and unbroken and ready at all times for a further attempt at starting.

In Fig. 3 a modification of the arrangement previously described is illustrated. In this figure the numeral 41 indicates an engine having a fly wheel 42 provided with a gear 43. The starting motor is indicated at 44, having the armature shaft 45, to which is secured the yoke member 46, this yoke member corresponding generally to the yoke member 7 previously referred to. Secured to this yoke member is a cam block 47 which may have screw threaded engagement therewith if desired, this cam block cooperating with a second cam block 48, the two blocks being provided with cooperating, complementary inclined cam faces in a manner similar to those previously described. These cam blocks are mounted upon a sleeve member 49, the block 47 being secured against axial movement by means of a pin 50 engaging a circumferential groove in the cam block. The cam block 48 is provided with an outstanding annular flange 48a at its end which serves to define a seat for a coil spring 52 surrounding the sleeve 49 and having its other end seated within a flange 53 carried by an abutment member 54. The abutment member 54 is adjustably secured to the sleeve 49, as by means of a set screw 55. In this case the opposite ends 56, 57 of the spring are secured respectively within openings in the block 48 and the abutment member 54, so that any relative turning movement of the latter members places the spring under torsional stress. The outer end of the sleeve 49 is internally screw threaded for engage-

ment with an externally threaded sleeve member 58 constituting a hub for a pinion 59, the member 58 being freely slidable upon the shaft 45 of the starting motor. A brake disk 60 bears against the outer face of the pinion 59, such brake disk being actuated by a coil spring 61 surrounding the armature shaft and bearing at its opposite end against a collar 62. This collar forms a fixed abutment for the spring, bearing against or forming an integral part of the bearing 62 in which the end of the armature shaft turns. The operation of the device just described is similar in general to that shown in the Figs. 1 and 2. When the armature shaft 45 is rotated, the cam block 47 is turned thereby forcing the cam block 48 longitudinally of the shaft placing the spring 52 under compression and also under torsional stress. When the spring has been compressed to a predetermined amount, further relative turning movement of the cam blocks is prevented and motion is transmitted through the spring to the abutment member 54 and thence to the sleeve 49. The sleeve or hub 58 is then drawn longitudinally into the sleeve 49 by reason of the screw threaded engagement of the parts, carrying pinion 59 into engagement with gear 43. When the pinion 59 abuts against the end of the member 54, the pinion is then constrained to turn with sleeve 49 thereby driving the gear 43 for starting the engine. In starting the engine, the spring 52 is then further stressed until its resistance is sufficient to overcome the inertia of the engine parts, whereupon the sleeve 49 and pinion 32 are rotated with the shaft 5, thus turning gear 3. When the engine has attained its normal speed, the pinion 59 rotates at a speed greater than that of the sleeve 49, and is thus backed out of the latter, removing the pinion from engagement with the engine gear. If during starting, the engine back-fires, the spring 52 is first placed under greater compressive and torsional strain until the high portions of the cam blocks pass each other whereupon the parts reassume the axial position of Fig. 3. If reverse rotation under the momentum of back-fire continues, the spring will be recompressed and the action will be repeated as often as may be necessary. While it is preferred to use the engaging, relatively movable cam elements in this specific construction, somewhat similar results might be attained by omitting them, and fixing the end 56 of spring 52 directly to the yoke 46, the spring in such case being made of sufficient length and resiliency to care for the added compression of back-firing. Such an arrangement however, would not permit unlimited reversal of the pinion, as is the case when the cam members are employed.

In Fig. 4 a further modification is illustrated in which the engine is shown at 71,

having the fly wheel 72 and the gear 73. The starting motor is indicated at 74, having an armature shaft 75 journalled in a fixed bracket 76. Secured to the armature shaft is a 5 yoke member 77, the end of which may, if desired, constitute one of the cam blocks, being beveled off or otherwise shaped to provide the desired cam surface. Within this yoke is journalled a sleeve 78 which is secured 10 against endwise movement relatively to the yoke by means of a pin 79 fixed in the sleeve and turning freely in a groove 80 in the yoke. A cam block 81 is also mounted upon the sleeve, this block having an end 15 face cooperating with the end face of the yoke and being secured against rotation relatively to the sleeve by means of a pin 82 engaging a longitudinal slot 83 in the sleeve. The cam block 81 is thus free to move longitudinally 20 of the sleeve while turning therewith. The outer extremity of the sleeve is provided with an integral shoulder or flange 84 and between such flange and the end of the cam block 81 a coil spring 85 is arranged, such spring surrounding 25 the sleeve and tending normally to force the cam block 81 toward the yoke 77. The sleeve 78 is provided with a bore 86 for the reception of a sleeve 87 mounted upon the armature shaft. This sleeve 87 is provided 30 with an enlargement 88 at its left-hand end, as viewed in Fig. 4, such enlargement being externally screw-threaded as shown at 89 for engagement with internal threads 90 on the inner surface of the bore 86. A pinion 91 is mounted on the sleeve 87, being secured 35 thereto by means of a set screw 92. A brake disk 93 is arranged to engage the end of the sleeve 87, or the hub of the pinion, as may be most convenient, such member 93 being 40 actuated by a coil compression spring 94 whose opposite end bears against a collar or flange upon the bearing 76. The member 93 thus constitutes a brake normally tending 45 to prevent rotation of the pinion 91. The operation of this device is substantially like that of the device illustrated in Figs. 1 and 2.

In Figs. 5, 6 and 7 a still further modification is illustrated. In these figures, the engine is omitted, the starting motor being 50 shown at 104, having the shaft 105 to which a yoke member 106 is secured by means of a set screw 107 or in any other suitable manner. The engine fly wheel is shown at 108, having the gear 109. The yoke member 55 106 comprises the hub 110 and a substantially annular portion 111 provided with a bore 112 concentric with the armature shaft. The member 111 is provided with a plurality of outstanding bosses 113, three of such bosses being illustrated herein, spaced equally about the circumference of the member 111. These bosses are 60 preferably integral with the latter member although not necessarily so. The several bosses are provided with radial bores which are internally screw threaded for the reception of adjusting bolts 114. The inner ends of such bolts are preferably chambered out as shown at 115, forming seats for the upper ends of springs such as 116. The lower 65 end of each spring 116 is received in a similar seat or chamber in a cylindrical, piston-like member 117 slidable within the inner ends of the bores. The inner end of each piston 117 is provided with an axially extending contact member 118, see Fig. 7. A sleeve 119 is mounted to turn freely upon the armature shaft, such sleeve at one end entering the bore 112 in the yoke member 106 where it is provided with a plurality of cam surfaces 120, 120^a, 120^b respectively cooperating with the several contact members 118. These cam surfaces are separated by the high points 121, 121^a, 121^b respectively, and are of concave curvature and preferably 70 symmetrical with respect to the axis of the shaft. In the normal position of the parts the contact members 118 engage such cam surfaces substantially at their central points. The sleeve 119 is provided 75 with an internally screw threaded bore, indicated at 122, with which engages an externally screw threaded hub member 123 secured to a pinion 124. Suitable brake means not shown, may be employed, if desired, for 80 restraining the pinion 124 from rotation until it has been moved into engagement with the gear 109.

In the operation of the device last described, rotation of the armature shaft 105 turns the yoke member 106, thereby causing the several contact members 118 to move along the cam surfaces with which they engage. The first effect of such movement is to place 85 the springs 116 under slight compression thereby turning the sleeve 119 and drawing the pinion 124 axially into engagement with the gear 109. As soon as the pinion 124 has been drawn into engagement with the gear 109 further rotation of the sleeve 119 is opposed 90 by the inertia of the engine parts. As the armature shaft 105 continues to rotate the springs 116 are now placed under greater compression until the compressive stress balances 95 the inertia of the engine parts whereupon the latter are driven by the armature shaft for starting the engine into operation. After 100 the engine starts, the pinion 124 backs out from the sleeve 117 in the manner described 105 with respect to previous arrangements. When the starting motor is stopped, the reaction of the contact members 118 upon the several cam surfaces 121, etc., tends to 110 restore the parts to the position of Fig. 5, although full restoration of the parts is not essential. If during starting, the engine backfires, the only effect is to cause abnormal compression of the springs 116 such as to permit 115 the contact members 118 to pass over the high points 121, etc., of the sleeve member, thus 120

125

130

permitting the latter to turn in a reverse direction as respects the armature shaft until the momentum of back-fire has been exhausted, whereupon the armature shaft picks up the parts for a further attempt at starting.

While the mechanism herein disclosed is particularly adapted for use in engine starters, it is contemplated that it may be useful 10 in other situations where it is desired to transmit power from one element to another, and particularly where it is possible that for some reason or other the driven element may be caused inadvertently to move in a reverse direction with force sufficient to break the driving connections if of ordinary construction.

It is also contemplated that other and additional variations and modifications of the 20 fundamental features of the invention herein disclosed may be employed from time to time without departing from the spirit of the present invention.

I claim:

25 1. A power transmission mechanism for engine starting comprising a power shaft, a sleeve co-axial therewith, cooperating cam elements carried by the shaft and sleeve respectively for transmitting motion of rotation from the former to the latter and arranged to slip by each other in the event of an abnormal amount of torque being transmitted to thereby operatively disconnect the shaft and sleeve, a spring means normally operative to determine the driving pressure between said elements, a screw shaft concentric with the sleeve and having screw threaded engagement therewith, said screw shaft having a driving member movable 30 axially therewith to engage a member of the engine to be started.

2. A mechanism of the class described comprising a rotatable shaft, a pinion mounted thereon for longitudinal movement thereof 45 to engage a member of the engine to be started and for rotary movement therewith, a source of power, and operating connections located between the pinion and source of power and consisting of two cooperating cam members, the first one of which is mounted 50 on the shaft to rotate independently thereof but restrained against longitudinal movement thereon, and the second one of which is mounted on the shaft for positive rotary movement therewith and for longitudinal movement thereon, a coiled spring encircling said shaft and cooperating with the second cam member to hold it in engagement with the first cam member, and an adjustable collar 55 arranged on the shaft and serving on one side as an abutment for the pinion and on the other side as an abutment for the spring.

3. A power transmission mechanism comprising a driving member and a driven member, one of said members having a cam ele-

ment normally engaging an element of the other and adapted to transmit all the driving torque that is delivered from the driving member to the driven member, and means normally operative to force said elements into 70 driving engagement with one another.

4. A power transmission mechanism comprising a driving member and a coaxial driven member, one of said members having a cam surface and the other having an element engageable with said surface, said cam surface and element transmitting all the driving torque that is delivered from the driving member to the driven member, and spring means normally operative to retain said surface and 75 element in driving engagement.

5. A power transmission mechanism comprising a driving member and a coaxial driven member, one of said members having an inclined cam face, and the other having an element engageable with said face, said cam surface and element transmitting all the driving torque that is delivered from the driving members to the driven member, and adjustable 80 spring means normally operative to retain said cam face and said element in driving engagement.

6. A transmission mechanism for engine starting comprising a power shaft, a sleeve coaxial therewith, a cam block rotating with the shaft, a second and axially movable block mounted upon the sleeve and connected for rotation therewith, said cam blocks having engaging cam faces, an abutment flange member secured to the sleeve, and a coil spring surrounding the sleeve and abutting against the flange member and second cam block and having its opposite ends secured to said flange member and block respectively.

7. A power transmission mechanism for engine starters comprising a power shaft, a supporting member coaxial therewith, a block rotating with the shaft, an axially movable block mounted on said supporting member, said blocks having engaging elements, a flange 100 adjustably secured to the supporting member and a torsion spring interposed between and connected to said flange and the axially movable block, respectively.

8. A power transmission mechanism for engine starting comprising a power shaft, a sleeve mounted freely thereon, a cam block rotating with the shaft, a second cam block splined to the sleeve and axially movable, said blocks having cooperable cam faces, a flange member mounted upon the sleeve and having threaded engagement therewith for adjustment axially therewith, and a coil compression spring encircling said sleeve and interposed between said flange and the axially 110 movable cam block.

9. A power transmission mechanism for engine starting comprising an armature shaft, a cam block fixed thereon, a sleeve freely mounted upon the shaft, a second cam block 115

75

80

90

95

100

105

110

115

120

125

130

splined to the sleeve for relative axial movement but for rotation with the sleeve, said cam blocks having engaging, complementary cam faces, an adjustable abutment upon the sleeve, a driving spring interposed between said abutment and the second cam block, a second sleeve mounted upon the shaft and extending within the first sleeve, said sleeves having screw threaded engagement with one another, a pinion carried by the second sleeve normally spaced from the first sleeve but movable axially with the second sleeve into engagement with the end of the first sleeve, and means operative during the early stages 15 of such movement to restrain the pinion against rotation.

10. A power transmission mechanism comprising a power shaft, a central supporting shaft, a sleeve loosely mounted thereon, a 20 yielding driving connection between the power shaft and sleeve, and a driving member mounted loosely on the central shaft and having a screw threaded hub said member and its hub bearing on such central shaft as to their entire length, said sleeve having at one end a screw threaded bore to receive said hub.

25 11. A power transmission mechanism comprising a power shaft, a central supporting shaft, a sleeve loosely mounted thereon, a yielding driving connection between the power shaft and sleeve, and a driving member connected with the sleeve for rotary movement therewith and longitudinal movement thereof, said yielding driving connection including two cooperating spring pressed cams, one of which is rigidly connected with the power shaft and the other is yieldingly connected with the sleeve through the spring.

30 12. A power transmission mechanism comprising a power shaft, a central supporting shaft, a sleeve loosely mounted thereon, a yielding driving connection between the power shaft and sleeve, and a driving member connected with the sleeve for rotary movement therewith and longitudinal movement thereof, said yielding driving connection including two cooperating spring pressed cams in the form of collars which are mounted upon the sleeve, one of the cams being rigidly connected with the power shaft and the other being yieldingly connected with the sleeve and having a yielding longitudinal movement relative thereto.

35 13. A power transmission mechanism comprising a power shaft, a central supporting shaft, a sleeve loosely mounted thereon, a yielding driving connection between the power shaft and sleeve, and a driving member connected with the sleeve for rotary movement therewith and longitudinal movement thereof, said yielding driving connection including two cooperating cams in the form of collars which are mounted upon the sleeve, one of the cams being connected with the power shaft and having means to prevent longitudinal displacement of the sleeve, and the other of which cams is mounted for longitudinal movement on the sleeve, and yielding means resisting longitudinal displacement of the last-mentioned cam.

40 14. A power transmission mechanism comprising a power shaft, a central supporting shaft, a sleeve loosely mounted thereon, a yielding driving connection between the power shaft and sleeve, and a driving mem-

ber connected with the sleeve for rotary movement therewith and longitudinal movement thereof, said yielding driving connection including two cooperating cams in the form of collars which are mounted upon the sleeve, one of the cams being connected with the power shaft and having means to prevent longitudinal displacement of the sleeve, and the other of which cams is mounted for longitudinal movement on the sleeve, and a spring connection between the sleeve and the last named cam.

45 15. A power transmission mechanism comprising a power shaft, a central supporting shaft in axial alinement therewith, a sleeve loosely mounted on such central shaft, a yielding driving connection between the power shaft and sleeve, and a driving member mounted loosely on the central shaft and having a screw threaded hub said member and its hub bearing on such central shaft as to their entire length, said sleeve having at one end a screw threaded bore to receive said hub.

50 16. A power transmission mechanism comprising a power shaft having a yoke, a central supporting shaft secured to the yoke at its axis of rotation, a sleeve loosely mounted on the central shaft, a driving member mounted on the central shaft and connected with the sleeve for rotary movement therewith and longitudinal movement thereof, and a yielding driving connection between the yoke and the sleeve.

55 17. A power transmission mechanism comprising a power shaft having a yoke, a central supporting shaft secured to the yoke at its axis of rotation, a sleeve loosely mounted on the central shaft, a driving member mounted on the central shaft and connected with the sleeve for rotary movement therewith and longitudinal movement thereof, and a yielding driving connection between the yoke and the sleeve, said driving connection including a collar connected with the yoke and having a cam face, and a spring pressed collar mounted loosely on the sleeve for longitudinal movement and having a complementary cam face.

60 18. A power transmission mechanism comprising a power shaft having a yoke, a central supporting shaft secured to the yoke at its axis of rotation, a sleeve loosely mounted on the central shaft, a driving member mounted on the central shaft and connected with the sleeve for rotary movement therewith and longitudinal movement thereof, and a yielding driving connection between the yoke and the sleeve, said driving connection including a collar adjustably connected with the yoke and having a cam face, and a spring pressed collar mounted loosely on the sleeve for longitudinal movement and having a complementary cam face.

65 19. A power transmission mechanism comprising a power shaft having a yoke, a central

supporting shaft secured to the yoke at its axis of rotation, a sleeve loosely mounted on the central shaft, a driving member mounted on the central shaft and connected with the sleeve for rotary movement therewith and longitudinal movement thereof, and a yielding driving connection between the yoke and the sleeve, said driving connection including a collar connected with the yoke and having a cam face, a second collar loosely mounted on the sleeve and having a complementary cam face, and a spring operatively connecting between the second collar and the sleeve.

19. A power transmission mechanism comprising a rotatable shaft, a yoke connected therewith, a sleeve loosely mounted on the shaft, a driving member connected with one end of the sleeve for rotary movement therewith and longitudinal movement thereof, and a yielding driving connection between the yoke and the sleeve, said yoke extending partially over the sleeve and encompassing the end thereof.

20. An engine starter drive including a driving member adapted to engage a member of an engine to be started, a driven shaft associated with said driving member to rotate it, a driving element, and a combined driving spring and clutch-structure operatively associating said driving element and said driven shaft for torque transmission through said clutch and spring and comprising a clutch held normally in engagement by the tension of said spring and adapted to be automatically de-clutched against the tension of said spring.

21. An engine starter drive including a driving member adapted to engage a member of an engine to be started, a driven shaft associated with said driving member to rotate it, a driving element, and a combined driving-spring and clutch-structure operatively associating said driving element and said driven shaft for torque transmission through said clutch and spring and comprising a clutch inherently tending to de-clutch under torque and normally held against de-clutching by tension of said spring.

22. An engine starter drive including a driving member adapted to engage a member of an engine to be started, a driven shaft associated with said driving member to rotate it, a driving element, and a combined driving-spring and clutch-structure operatively associating said driving element and said driven shaft for torque transmission through said clutch and spring and comprising a clutch inherently tending to de-clutch under torque and having an element, movable for de-clutching, connected with said spring and normally held against de-clutching by tension of said spring.

23. In combination, a one-piece sleeve and pinion member adapted to be mounted on a driving shaft, a threaded nut on said sleeve,

said sleeve having a threaded portion with a shoulder at the rear end of the threaded portion, an attaching collar mounted on and secured to the motor shaft, and a helical connecting spring between the collar and the nut. 70

24. An engine starter drive including a power-driven shaft, an externally-threaded sleeve mounted for movement on a smooth portion of said shaft and carrying a driving member adapted for longitudinal movement 75 to engage and rotation to crank a member of the engine to be started, an internally threaded nut member engaging said threaded sleeve, and a combined driving-spring and clutch-structure operatively associating said shaft 80 and said sleeve for torque transmission through said clutch and spring and including a clutch held normally in engagement by tension of said spring and adapted to be automatically declutched against the tension of 85 said spring.

25. An engine starter drive including a power-driven shaft, an externally-threaded sleeve mounted for movement on a smooth portion of said shaft and carrying a driving 90 member adapted for longitudinal movement to engage and rotation to crank a member of the engine to be started, an internally threaded nut-member engaging said threaded sleeve, said nut-member and sleeve having co-operative stop-provisions arranged for coaction when the driving member reaches a position for adequate engagement with the engine-member and a helical drive spring concentric with the shaft and operatively interposed between said shaft and said nut-member 95 to yield under torque transmission from the former to the latter. 100

CERTIFICATE OF CORRECTION.

Patent No. 1,883,342.

October 18, 1932.

ALBERT A. DENSMORE.

It is hereby certified that the residence of the assignee in the above numbered patent was erroneously written and printed in the grant and heading to the printed specification as "Elmira, New Jersey" and "Elmira Heights, New Jersey" respectively, whereas said residence should have been written and printed as Elmira Heights, New York, as shown by the records of assignments in this office; and that the said Letters Patent should be read with this correction therein that the same may conform to the record of the case in the Patent Office.

Signed and sealed this 25th day of February, A. D. 1936.

Leslie Frazer

(Seal)

Acting Commissioner of Patents.
